Primary Examiner — Robert M. Spear(74) *Attorney, Agent, or Firm* — Hayes Soloway PC(57) **CLAIM**

The ornamental design for a spherical speaker, as shown and described.

DESCRIPTION

1. Spherical speaker

1.1 : Perspective

1.2 : Front

1.3 : Right

1.4 : Back

1.5 : Left

1.6 : Top

1.7 : Bottom

1 Claim, 7 Drawing Sheets(56)
